UNITED STATES PATENT OFFICE.

JOHN M. BOYD, OF FOND DU LAC, WISCONSIN.

SUSPENDED TRACK FOR ELEVATORS AND CARRIERS.

No. 812,477.

Specification of Letters Patent.

Patented Feb. 13, 1906.

Original application filed December 23, 1901, Serial No. 87,029. Divided and this application filed May 20, 1903. Serial No. 158,010.

To all whom it may concern:

Be it known that I, JOHN M. BOYD, a citizen of the United States, residing at Fond du Lac, in the county of Fond du Lac and State 5 of Wisconsin, have invented certain new and useful Improvements in Suspended Tracks for Elevators and Carriers, of which the following is a specification, this being a divisional application of that filed by me December 23, 1901, Serial No. 87,029, for hay-carrier and track apparatus.

My invention relates to improvements in tracks adapted to be suspended in the peak of a barn or in other places where it is desired 15 to elevate hay or other material and to deliver it at different points along underneath a track by means of an elevator and carrier adapted to travel thereon, and has for its object to provide an apparatus of simple, strong, 20 and durable construction, easily and quickly put up and secured in place, and adapted to safely support the carrier close up to the rafters or other overhead support (allowing sufficient room to travel back and forth thereon) 25 and allow loads to be pulled in close up to the track easily and quickly without danger of cramping or binding either the carrier or track, and easily taken down when desired; and it consists in the improved construction, 30 combination, and arrangement of the various parts, substantially as shown in the drawings and pointed out in the claims.

In the accompanying drawings, in which similar letters of reference indicate corresponding parts, it will be noticed that the track-rail (which may consist of either a single T-rail or two pieces of angle-rail clamped together) is formed with a central stiffening or supporting part, to which the supporting 35 hangers or hooks are attached, and lateral or side extensions or flanges upon which the carrier-wheels may run in the usual manner, splice-clamps being also provided for splicing or clamping together different sections of 40 rail to make a track of any desired length without drilling or riveting, and end stops to prevent the carrier from running off the end of the rail, the body of the carrier being carried underneath the rail by side arms or hangers 45 attached to the wheels on the track in the usual manner, as shown in my former application noted above, of which this is a division. 50

In the drawings, Figure 1 is a detail view 55 of the different parts of the hanger-hook or track-hanger, showing how it is constructed

and attached to a single or T rail. Fig. 2 is also a detail view of the same form of hook with the different parts in place, being locked both to the track-rail and to the supporting 60 rafter iron or bracket, and showing the end stop for the carrier hooked in place in the rafter-bracket. Fig. 3 is a cross-section of the binding block and clamp for track formed with two angle-rails, also detail views of the 65 parts separately and in position for use. Fig. 4 is a side elevation and rear end view of the track hanger or hook formed for use with this style of rail. Fig. 5 is a detail view of the splice-clamps for splicing together dif- 70 ferent sections of the two styles of rail. Fig. 6 is a detail view of a modified form of the hanger-hooks, showing how the sides may be tied together close across the top of the rail; and Fig. 7 is a detail view of a modified form 75 of the hook and binding-clamp adapted for a double rail.

In the drawings, *r* represents the rafter-bracket adapted to be attached to the rafters or other supports in the ordinary manner. 80

h h' h⁴ h⁵ h⁶ are the hanger-hooks or track-hangers adapted to be hooked into the rafter-brackets *r* or other overhead support to support the track-rail, being wedged or keyed to said solid or T rail *T*, Figs. 1 and 2, by a supporting wedge or key *d'*, clasping one side of the upper bead of said rail, the lower end of the hanger-hook being formed to engage under said bead on the opposite side of the rail and the upper part of said wedge or key *d'* 90 being formed with lateral ribs or side extensions *d³* and adapted to pass through an opening in the body of the hook parallel with the rail, as in Fig. 2, thus clasping and supporting said rail by the upper bead, as shown, 95 when the closing-link *r'*, Fig. 1, may be put in place, as in Fig. 2, and the ends bent around or closed, thus locking the wedge or key *d'* in the hook and the upper end of the hook in the bracket *r*, as shown, and at each end of 100 the track the end stop *r²*, formed in the shape of a loop, with the ends adapted to pass up each side of the rail, may be hooked at its upper end into the rafter-bracket, as shown, ready to catch and stop the carrier, as will be 105 readily understood.

When two parallel rails *n n* are used instead of one single T-rail, as in Figs. 3 and 4, the supporting wedge or key is formed with lateral or side extensions *s s*, as at *d²*, Fig. 4, at the lower end, to support both rails, the upper end being provided with lateral ribs and pass-

ing through the body of the hook h' , the same as the other form of wedge or key through the hook h when a single rail is used, the lower ends of the hook h' extending down at each side of the rails $n\ n$, as shown, to hold them in place, and the supporting - wedge may be locked in place by a key or pin J , as shown, leaving the upper part of hook open in either style of hook, or the closing-link r' may be used, thus closing the hook also, as in Fig. 2, as desired, or a rivet or key may be passed through the eye in the end of said wedge, or said eye or extension may be bent around and clenched, if desired, when made malleable, or the wedge otherwise secured.

The track hangers or hooks may also be formed with recesses or guideways at each side, as between the lugs or extensions $h^2\ h^3$, to form a guide for and to receive and support the stop or trip block for the carrier, as shown in my former application referred to above, if desired, especially for use at the point where load is raised, (or wherever it may be desired to attach a stop at times,) thus holding the stop up, so that the endwise strain when load is being raised will come up against the rafter-brackets and rafters and relieve the track-rail and also support the stop in position both above and below and hold it parallel with track and leave the under side of the rail clear, with either a double or single rail track.

n^3 , Fig. 3, is a binding-block formed with side extensions $s\ s$ at the lower end, similar to the supporting-wedge d^2 , Fig. 4, and an extension or hook n^7 at the upper end, also short lateral ribs or extensions forming a head n^2 , similar to the supporting-wedges $d^1\ d^2$, Figs. 1, 2, and 4, said blocks being adapted to be placed at short distances apart between the rails $n\ n$ when two rails are used, as shown in detail and sectional views in said Fig. 3, and clamped in place by binding-clamps C , formed with downwardly-extending sides $n'\ n'$ to hold the rails in place and inwardly-extending ribs or extensions $n^6\ n^6$ to pass underneath the side extensions of the head n^2 of each binding-block n^3 (being similar to the lower end of hook h' , Fig. 4) and resting on the upper edges of the rails, as shown, the sides n' being connected at the ends across the rails, the cross-bar or loop formed at one end being extended out beyond the inside ribs $n^8\ n^8$ far enough to allow the clamp to be passed down over the head n^2 of the said binding-block n^3 and slid along on the rails until clamped tightly in place, as shown, with the cross-bar at the opposite end under the hook n^7 , thus greatly stiffening the rails and holding them together between the hangers.

$H\ H$, Fig. 5, are two similar sides or plates of a splice-clamp, which, being preferably duplicates and reversible and adapted to fit into each other at the top and ends above the rail to prevent endwise movement and being clamped together against each side of adjoin-

ing ends of the single rail T , with bolts across the top of the rail, as shown, form a simple and reliable splice-clamp. In the same figure is also shown another form of splice-clamp n^4 , for use between two angle-rails $n\ n$, being formed with a lower part s extending sidewise underneath the rails similar to the key or wedge d^2 , Fig. 4, and binding-block n^3 , Fig. 3, to support the rails, which rails may be spliced by breaking joints, if desired, as will be understood, the ends of joined rails being shown in dotted lines, the other in full lines, said splice-clamp being formed with upper extensions or heads n^5 at each end, similar to the head n^2 of the binding-block n^3 , Fig. 3, (and also quite similar to the head of supporting-wedge d^2 , Fig. 4,)and for the same purpose, the binding-clamps n' , Fig. 3, being slipped down over said heads n^5 at each end and pushed or driven along into engagement therewith in the same manner as with the binding-block n^3 , heretofore described, thus locking it firmly and clamping the rails together, and to further secure the same in either case a wedge may be driven into the extending loop at the end, or a bolt B and washer may be used, as shown, passing between the rails, and the nut of said bolt may be locked in place by a pin or key J , as shown, or the clamp may be secured by said pin or key alone, or otherwise, similar to the supporting-wedges $d^1\ d^2$, Figs. 2 and 4.

At $h^4\ h^5$, Fig. 6, are shown modified forms of the hooks $h\ h'$, Figs. 2 and 4, (not shown in former application,) said hooks being formed with cross-ties E at the front, close above the track-opening, and with recesses at the rear, into which hooks or extensions $m\ m$, formed on the supporting-wedges $d^3\ d^4$, engage above the rail to prevent the lower parts of the hooks from spreading or opening. $h^6\ h^6$, Fig. 7, represent also another modified form of the track hanger or hook for the double rail, (also added to this application,) showing the same in side and edge views, the hook in this case being formed in one continuous piece extending down between the rails and being provided with lateral projections or side extensions at the lower ends, similar to those at $s\ s$ on the supporting-wedge d^2 , Fig. 4, and also the splice-clamp n^4 , Fig. 5, and binding-block n^3 , Fig. 3, to support the rails, a binding-clamp C' being provided for use with this form of hook, similar to that shown at C , Figs. 3 and 5, and having downwardly-extending sides $n'\ n'$ and inwardly-projecting lugs $n^6\ n^6$ for the same purpose, except that in this case the cross-bars at the ends above the rails are not extended out into loops and the inwardly-projecting lugs $n^6\ n^6$ are formed with openings to allow outwardly-projecting lugs or extensions $n^8\ n^8$, formed on each side of the body of the hook, to pass through as the said clamp is slipped down over the hook and astride the rails when a looped key or staple l (or two straight nails, keys, or pins) 130

may be driven in between the lugs n^6 of the clamp and the lugs n^8 of the hook, as shown, instead of driving the clamp along on the rail, as in Figs. 3 and 5, thus locking the clamp 5 and hook, when the ends of said key or staple may be clenched back, as shown in dotted lines at l at the left of the figure, to secure the key from working out, or said clamps may be formed with one end open, to be 10 closed with a bolt or otherwise after being slipped or driven in place in either case, as it is also evident that this modification may be used for the splice-clamp and binding-block shown in Figs. 3 and 5 also.

15 Either form of this track-rail when put together with the splice-clamps, track-hangers, and end stops, as described, to form a complete track and hung in the rafter-brackets or other overhead support, will form a swing-20 ing track supported along its center and adapted to allow the carrier-wheels to pass at each side of its central supports and splices and clear underneath to allow hay, &c., to be dragged in close up, the stop-block for the 25 carrier being supported close up to the rafters, as heretofore described, and there being no depending end of hangers, splices, &c., to interfere, and the same carrier may be used on either style of rail, and both carrier and 30 track may be easily put up and secured in place or taken down, if desired, as will be readily understood from the foregoing. It is evident that rails of different shapes in cross-35 section may also be used with these hangers, clamps, &c., the lower ends of the track-hangers, the wedges or keys and clamps, &c., being formed to fit the rails, also that the upper ends of the hangers may be made in the form of a loop, if desired, though I prefer the 40 hooked shape as being more easily put up or taken down separate from the rafter-brackets, (or floor-hooks, when used in a ridge-piece,) also that other modifications may be made without departing from the spirit of 45 my invention, and I therefore wish it distinctly understood that I reserve to myself all such modifications, parts, and combinations as properly come within the scope of my invention and for all purposes for which 50 they may be found to be adapted and useful.

What I claim as my invention, and desire to secure by Letters Patent, is—

1. In a suspended track apparatus for elevators and carriers, in combination with a 55 suitable track rail or way, a track-hanger provided with an upper extension by which it may be suspended, and formed at the lower end to engage with the track rail or way, a separate wedge or key adapted to key 60 the same to said track rail or way to support said rail, and separate or independent means to secure said wedge or key in place endwise, substantially as and for the purposes set forth.

2. In combination with a suitable track 65 rail or way, a track-hanger adapted to be sus-

pended from a rafter-bracket or other support, and formed with an opening or channel through its body at or near the lower end to receive a wedge or key, a wedge or key adapted to engage in said opening and lock the 70 hanger to the track-rail, and means to secure said wedge in place endwise, substantially as and for the purposes set forth.

3. In combination with a suitable track rail or way, a track-hanger formed with an 75 upper extension by which it may be suspended, and an opening, channel, or key-seat, through its body parallel with the track-rail, and a suspending and clamping device adapted to engage with the track-rail, and formed 80 with a head, wedge, or key, at its upper end adapted to engage in said opening or key-seat in the track-hanger proper, substantially as and for the purposes set forth.

4. In combination with the track rail or 85 way, a track-hanger adapted to be connected with a support above the rail, and formed at its lower end to engage with the rail or way, and provided with an intermediate opening or key-seat through its body parallel with the 90 rail, and a key or wedge adapted to engage in said opening and formed with a lower part or extension adapted to support and hold the rail or way in proper position in conjunction with the lower end of the main part of said 95 track-hanger, substantially as and for the purposes set forth.

5. A track-hanger formed with means for connecting with an overhead support, and adapted to connect with a track rail or way 100 at its lower end, and provided with an intermediate opening or key-seat parallel with the track, and a lower part adapted to engage with the track-rail, and formed with a head at its upper end provided with lateral ribs or 105 lugs adapted to engage in said opening in the main part of the hanger and lock the same in connection with the track-rail, substantially as and for the purposes set forth.

6. A track-hanger formed with an upper 110 or main part adapted to be connected with an overhead support, and a lower part adapted to engage the track-rail, and means whereby said upper and lower parts may be wedged or keyed together endwise to support the rail 115 in proper position, substantially as and for the purposes set forth.

7. A track-hanger consisting of an upper supporting part adapted to engage with the rail at its lower end, a lower part adapted to 120 engage with said upper part above the rail through its center, and lengthwise of the track, and hold the same in locked engagement with the rail, and extraneous means to prevent the disengagement of the parts by 125 the rattle and jar of the track while in use, substantially as and for the purposes set forth.

8. A track-hanger formed with a hooked upper end to engage with a rafter-bracket or 130

other support, a lower end adapted to engage with the track-rail, means for connecting said lower end in locked engagement with the track-rail, and a rod or link to connect said means with said hook and lock them both in place, substantially as and for the purposes set forth.

9. A track-hanger formed with a hooked upper end, and adapted to engage with the track-rail at its lower end, and provided with an opening or channel through its body adapted to receive a wedge or key, a wedge or key adapted to engage in said opening and clamp said hanger to the rail, and a rod or link adapted to lock said wedge in said opening and connect the same with the hook, substantially as and for the purposes set forth.

10. A track-hanger formed with an upper suspending part adapted to receive and support the upper end of a lower or clamping part, a lower part adapted to clamp or wedge said upper part to the track-rail, and a rod, key, or link, adapted to hold said upper and lower parts in proper connection with each other from endwise movement.

11. A track-hanger formed with an upper or suspending part, and a lower or clamping part formed with a head to engage in an opening in the upper part, said parts being adapted to wedge together to support the track from an overhead support, and means to hold the same in proper engagement with each other.

12. A track-hanger formed with an upper hooked part, a lower clamping part, said parts being adapted to wedge together to support the track-rail, and a rod or link adapted to hold or lock the same together endwise and to close the opening in the hook.

13. A track-hanger formed with an upper hooked part, a lower clamping part adapted to engage inside said upper hooked part, said parts being adapted to slide or wedge together lengthwise with the rail, and a rod or link adapted to hold the same together against an endwise movement, and to close the opening in the hook.

14. The track-hanger *h* formed with an opening through its center, and the clamping or supporting wedge *d'*, in combination with the track-rail *T*, and means for holding the same together against an endwise movement along the track.

15. The combination of the track-hanger *h* formed with a central channel, the clamping and supporting wedge *d*, the rod or link *r'*, and the track-rail *T*, substantially as and for the purposes set forth.

16. In combination with the track rail or way, a track-hanger adapted to support the rail, and provided with a guideway, or means to guide the attachment of the stop-block of a carrier in proper place at the side or sides of said hanger, substantially as set forth.

17. In combination with the track or way,

a track-hanger adapted to support the track-rail, and provided with lugs or extensions at each side above the track to support a stop or trip block of a carrier, substantially as set forth.

18. In combination with a track rail or way, a clamping device formed in separate pieces provided with ribs or lugs adapted to fit into and engage with each other at their upper edges, above the rail, and means to hold the same together, substantially as set forth.

19. In combination with a track rail or way, a clamping device formed in separate parts provided with lateral extensions or lugs at or near their upper edges adapted to engage with each other at each side of the center of the track or way, and lower extensions adapted to engage and hold the track in position, and means whereby the same may be clamped together, substantially as and for the purposes set forth.

20. In combination with the track rail or way, a clamping device formed with upward extensions provided with lateral ribs or lugs adapted to engage with each other and be clamped together at each side of the center, cross extensions at each end, and means for holding the parts in engagement with each other, substantially as and for the purposes set forth.

21. In combination with the track rail or way, a clamping or binding device formed with an upward extension or head provided with side lugs or ribs and a horizontal extension or lug above the rail, and a wedge or clamp adapted to engage underneath said horizontal extension and said side lugs or ribs and clamp the same to the rail, substantially as and for the purposes set forth.

22. In combination with a suitable track rail or way, a clamping or binding device formed with a supporting part having an upwardly-projecting extension or head provided with lateral lugs or ribs above the track, and a clamping part formed with inwardly-projecting lugs or ribs, and a loop or cross-bar at each end, and adapted to be passed down over said head, and moved horizontally along said track-rail into locking engagement with said head, substantially as and for the purposes set forth.

23. In combination with the track-rail, a clamping and supporting device provided with lateral extensions, lugs, or ribs, lengthwise of and above the rail, and formed at the lower end to engage with the rail, and means whereby the same may be clamped to the rail underneath said lateral lugs or ribs, substantially as and for the purposes set forth.

24. In combination with a track rail or way, a clamping or binding device formed with a supporting part provided with an upper extension or head formed with side extensions, ribs, or lugs, and a projection *n'*, and a clamping part provided with inwardly-

projecting lugs or ribs n^6 ; n^6 , adapted to engage with said side extensions or ribs on said head, and downward extensions adapted to engage and hold the rail, substantially as and for the purposes set forth.

5 25. In combination with a suitable rail or way adapted for a carrier to travel thereon, an end stop for said carrier adapted to be pivotally suspended from an overhead support above the track to prevent said carrier from leaving the track at the end, substantially as set forth.

15 26. In combination with a suitable rail or way adapted for a carrier to travel thereon, an end stop for said carrier adapted to hook into a support above the rail and adapted to catch and stop the carrier, substantially as set forth.

20 27. In combination with a suitable rail or way adapted for a carrier to travel thereon, and an overhead support for said rail or way, an end stop flexibly suspended from said overhead support directly above the rail and adapted to catch and stop the carrier, substantially as and for the purposes set forth.

25 28. In combination with the track or way adapted for a carrier to travel thereon, an end stop for said carrier formed in the shape of a loop into which the carrier-wheels will 30 run, said loop passing preferably underneath the track and being connected to an overhead support, substantially as and for the purposes set forth.

30 29. In combination with the track rail or way, the rafter-bracket r and the loop or end stop r^2 , substantially as and for the purposes set forth.

35 30. In a suspended track, in combination with the rail or way provided with an upper

bead, a suspending hook or hanger formed 40 with an opening through its body parallel with the rail, whereby it may be attached to the rail, and a hooked extension at its lower end adapted to engage underneath one side of the upper bead of the rail, and a supporting wedge or clamp adapted to engage in said opening to clamp said hanger to the rail, and provided with a lower extension or hook 45 adapted to engage underneath the opposite side of the upper bead of the rail, substantially as and for the purposes set forth.

50 31. In a suspended track, in combination with the rail or way, hanger-hooks whereby said rail or way may be suspended, clamps whereby different sections of said rail may be 55 spliced or clamped together, and the end stops suspended above the track-rail at each end, substantially as and for the purposes set forth.

55 32. In a suspended track for elevators and carriers, the combination of the track-rails, splices or clamps to connect said rails, track-hangers whereby said rails may be suspended from an overhead support, supporting wedges or keys to connect said hooks with said rails 60 at suitable distances, and end stops or loops supported above said rails at each end of track, the whole constituting a complete suspended or swinging track, substantially as and for the purposes set forth.

70 In testimony whereof I hereby affix my signature, this 16th day of May, 1903, in presence of two subscribing witnesses.

JOHN M. BOYD.
